UNITED STATES PATENT OFFICE.

FRANK C. GROSSKOPF, OF SAN DIEGO, CALIFORNIA.

DESIGN FOR A HINGE.

43,419.

Specification for Design.

Patented Jan. 7, 1913.

Application filed September 11, 1912. Serial No. 719,888. Term of patent 7 years.

To all whom it may concern:

Be it known that I, FRANK C. GROSSKOPF, a citizen of the United States, residing at San Diego, in the county of San Diego and State of California, have invented a new, original, and ornamental Design for Hinges, of which the following is a specification, reference being had to the accompanying drawing, forming a part thereof.

Figure 1 is a perspective view of a hinge, disclosing my new design therefor. Fig. 2 is a plan view of the hinge.

The hinge leaves have ornamental edges and ornamental slots as shown.

I claim:

The ornamental design for a hinge, as shown and described.

In testimony whereof, I hereunto affix my signature, this 31st day of July, in the year 1912.

FRANK C. GROSSKOPF.

In the presence of—

FREDERIC M. KEENEY,
S. R. HYAMS.
